RING COMPRESSOR CONTROL DEVICE

Leon B. Miller, Brooklyn, N. Y.

Application September 30, 1940, Serial No. 359,085

5 Claims. (Cl. 188—81)

The present invention relates to piston ring compressors such as covered by my Patent No. 2,208,136, issued July 16, 1940, and particularly deals with the control means governing the operation and release of the device during operation. In the aforesaid patent, the construction of the ring compressor broadly consists of a piston ring engaging strip intended to always assume a substantially true cylindrical form, a pair of compression bands designed to engage the edges of the strip for controlling the perimeter of the spirally wound, substantially cylindrical form of the strip, and a rotatable element, secured at one end of the strip in a suitable mounting, for operating the bands, said rotatable element being provided with a ratchet wheel, and said mounting supporting operative detent means, the latter being adapted to either engage or disengage said ratchet wheel, for retaining the rotatable element and said band in wound or adjusted position, or for releasing them to freely unwind, respectively.

The present invention has for its prime object to provide ratchet wheel detent means of a simplified form and capable of instantaneously engaging or releasing the ratchet wheel, the operation of the detent means to a releasing position requiring but a simple hand motion, as compared with the somewhat complicated sliding movement of the device covered in the aforesaid patent.

The foregoing object and numerous practical and important advantages of the present invention will become more fully apparent from the ensuing description and the accompanying drawings, in which

Fig. 1 is a top view of my ring compressor in its presently preferred form;

Fig. 2 is a side elevation thereof;

Fig. 3 is a vertical cross section through the ratchet portion of my device; and

Fig. 4 is a cross section taken on line 4—4 of Fig. 3.

Referring now specifically to the drawing, numeral 10 denotes the piston ring engaging strip of my device, which is wound in a spiral and is intended to assume and retain a substantially circular form always. At the outer end of strip 10 there is provided a mounting 11 which consists of a broad plate, bent upon itself and substantially reduced in width at its bent portion to form a substantially tubular loop or bearing 12. Extending from this bearing and associated with the outer and inner surfaces of strip 10 are outer and inner legs 13 and 14 of the mounting, permanently held in position by rivets 15, or other

suitable means. Outer leg 13 is bent up at 16, as clearly seen in Figs. 1 and 4, so that a space is provided between interior leg 14 and the bent-up portion of exterior leg 13.

Lodged within loop 12 is a rotary element 17, provided with end flanges 18 and 19 and ratchet wheels 20. Between the end flanges and the ratchet wheels are removably anchored the windable or free ends of bands 21, whereas their fixed ends are held in place beneath leg 13 of the mounting. These bands encircle strip 10 and are intended to either draw strip 10 together, or release it when the perimeter of the strip is to be changed. The upper end of rotary element 17 is provided with a socket 22 for the reception of a key or wrench 23, shown in Fig. 2.

The spaced portions of the two legs 13 and 14 of mounting 11, are indicated by numerals 24 and 25, respectively. These two leg portions are rendered adjustable towards or from each other, whereby loop 12 may be either tightened or loosened with respect to rotary element 17. Through such adjustment the operation of element 17, induced by resilient strip 10 and bands 21, may be governed. The aforesaid adjustment is preferably accomplished by an adjusting screw indicated at 26.

Straddling the raised leg portion 24 of the mounting there is arranged a detent 27, adapted to normally engage ratchet wheels 20. This detent is preferably made from a single strip of material, which is bent upon itself at 28 to form an outer leg 29 and an inner leg 30. The inner leg is provided with pawls or prongs 31 adapted to engage the teeth of ratchet wheels 20. This inner leg 30 of the detent operates within the space between raised portion 24 of outer leg 13 and the portion 25 of inner leg 14 of the mounting.

Near the bent-over end of the detent are provided registering apertures for the reception of screw 32, which extends freely through raised portion 24 of the mounting and engages threads provided in the lower portion 25 thereof. Screw 32 serves as a pivot for detent 27. Both the upper and lower leg portions of the detent are provided with suitable recesses 33 and 34 for accommodating and clearing adjusting screw 26.

Extending from the interior portion 30 of the detent is a projection 35 in which is mounted a spring member 36. The latter bears against the closed end of the pocket formed between leg portions 24 and 25 of the mounting and is intended to normally urge detent 27 towards ratchet wheels 20. From the upper leg of the detent extends a handle 37, conveniently placed to read-

ily facilitate the operation of the detent by the pressure of the thumb. When extension 37 is moved away from ratchet wheels 20, against the tension of spring 36, pawls or prongs 31 are caused to disengage ratchet wheels 20, thereby releasing rotary element 17.

Operation

When a piston with piston rings in its grooves is to be inserted into a cylinder, strip 10 is placed over the piston rings and is drawn together by the operation of handle 23, in that rotary element 17 is turned to wind up bands 21 until strip 10 completely engages and compresses into the grooves the rings of the piston. When this is accomplished, the piston, with the ring compressor holding the rings in the groove, is placed over the cylinder so that the notches 38, provided at the bottom edge of strip 10, rest against the edge of the cylinder into which the piston is to be inserted. Now the piston is pressed into the cylinder. As the rings, held within their grooves by strip 10, enter the cylinder one after the other, they automatically are released from the strip. When the entire piston is completely inserted, the compressor may be removed for use with the next piston. In order to release strip 10, extension 37 is pressed in the direction away from ratchet wheels 20, whereby prongs 31 are caused to disengage the teeth of the ratchet wheels, and compression bands 21 are unwound by the pressure exerted against them by the expanding, freed strip 10. In order to prevent too rapid an expansion of strip 10, adjusting screw 26 may be first tightened and then loosened for governing the friction upon rotary element 17.

While I have shown in the drawing but a single embodiment of my invention, be it understood that changes and improvements in its construction may be incorporated, without departing from the broad scope of my invention as defined by the annexed claims.

I claim:

1. In a ratchet device for controlling the operation of rotary elements powered by windable springs, such as employed in compression band type piston ring compressors, a rotary member provided with a ratchet wheel, a mounting forming the journal for said rotary member and having compressible spaced and fixed adjacent extensions, a spring induced detent pivotally mounted within said spaced extensions and adapted to normally bear against said ratchet, said detent having means for manually moving it away from the ratchet.

2. In a ratchet device for controlling the operation of rotary elements powered by windable springs, such as employed in compression band type ring compressors, a rotary member provided with two spaced ratchet wheels, a looped mounting forming the journal for said rotary member and terminating in compressible spaced and fixed adjacent extensions, a piston ring engaging strip secured to the fixed extension, 10 means for adjusting said spaced extensions, a detent for engaging said ratchet wheels pivotally mounted within the spaced extensions and straddling one of them, a resilient member associated with said detent and bearing against the 15 piston ring engaging strip held between said adjacent extensions of the mounting, said resilient member normally urging the detent against the ratchet wheels, and means provided on the detent for facilitating its movement manually away 20 from the ratchet wheels.
3. In a ratchet device for controlling the operation of rotary, spring-powered elements, a rotary member having a ratchet wheel, a looped mounting forming the journal for said member 25 and having adjustable spaced and fixed adjacent termini, the latter serving for attachment between them of a flat element, a ratchet wheel detent pivotally mounted within said spaced termini and straddling one of them, a resilient 30 element fastened to said detent and bearing against the flat element held between said adjacent termini and normally urging the detent against the ratchet wheel, and a handle provided 35 on the detent for moving it against the tension of the resilient element, and thus away from the ratchet wheel.
4. In a ratchet device, a rotary member having a ratchet wheel, a plate looped about said member and having spaced and adjustable 40 termini, forming the journal for the member, a detent pivotally mounted within said termini and normally engaging said ratchet wheel and having means for moving it away from the ratchet wheel.
5. In a ratchet device, a rotary member having a ratchet wheel, a journal for the member comprising a plate looped about the latter and having spaced and adjustable termini, a detent 45 pivotally mounted within said termini and straddling one of them and normally engaging said ratchet wheel and having means for moving it away from the ratchet wheel.
